PRESSING MACHINE

George W. Johnson, Cincinnati, Ohio, assignor to
The American Laundry Machinery Company,
Norwood, Ohio, a corporation of Ohio

Application July 18, 1934, Serial No. 735,799

8 Claims. (Cl. 68—9)

This invention relates to pressing machines of the type used in garment and laundry work and particularly to a machine adapted to produce pressing action simultaneously along two surfaces located at a substantial angle to each other.

An object of the invention is to provide a pressing machine having a pair of pressing members provided with central pressing portions and coacting side portions which coact in a plane generally at an angle to the meeting plane of the central portions. The invention provides means for moving the central portions into pressing engagement and means for moving the side portions into pressing engagement, together with one actuator for both means.

The invention provides also mechanism for moving the central pressing portions into pressing engagement, this mechanism having a lost motion connection permitting an additional movement beyond the point causing pressure engagement between the central portions, this additional movement being effective to move the side pressing portions into engagement.

Other objects and advantages will appear from the accompanying description taken together with the drawing, in which Fig. 1 is a side elevation of a pressing machine embodying my invention, partly broken away the better to show the construction, the parts are shown in open position in full line, and in dot-dash lines the parts are shown with the central portions in pressure engagement and before the side portions are moved into coacting position; Fig. 2 is a view similar to Fig. 1, showing the press completely closed; while Fig. 3 is an enlarged fragmental section taken transversely of the bed and head, showing the details of construction.

The press illustrated comprises a frame 10 on which is mounted a pedestal 11 which supports a bed 12. An upstanding bracket 13 on the frame pivotally supports a head lever 14 which carries a pressing head 15 adapted to coact with the bed 12. The head is provided with a central pressing portion 16 and depending side portions 17 extending at a considerable angle to the general plane of the portion 16, as shown in the drawing.

The pressing members 12 and 15 are of a type similar to that used in the pressing of articles such as men's shirts, that is to say, the central portions of the pressing members are of considerable area such as would be adapted to press the front or back of a shirt, while the side pressing portions are of sufficient extent to press a portion of the side of a shirt body. Ordinarily, therefore, my invention contemplates the provision

of central portions of somewhat greater area than the side portions.

Means is provided for moving the head toward and away from the bed, which comprises a double toggle mechanism, one set of toggles comprising the members 18 and 19 extending between the frame 10 and the rear end of the head lever. The connection between member 18 and the head lever comprises a reduced portion 20 on the toggle 18 which has an operative engagement with a rotatable pin 21 in the head lever. A spring 22 surrounds the reduced portion 20 in a position adapted to be compressed between a shoulder 23 on the toggle 18 and the head lever 14, thus exerting yielding pressure against the rear end of the head lever when the toggles are moved to straightened position so that after the head moves to the dot-dash position of Fig. 1 to exert pressure between the coacting central portions of the pressing members the toggle mechanism is movable farther to the straightened position of Fig. 2, which advances the reduced portion 20 of toggle 18 through the coacting pin 21 on the head lever which at the same time takes up somewhat on the spring 22. This additional movement is utilized to move the coacting side pressing portions into pressing engagement, as will be later described. The means provided for straightening the toggle mechanism 18—19 comprises a second toggle mechanism comprising link 24 pivotally connected at one end to the first described toggle mechanism and at its other end connected to a lever 25 pivotally supported at 26 on the frame. The lever 25 in turn is connected by a link 27 to a treadle 28 which is pivotally mounted at the rear of the frame, thus pressure downwardly on treadle 28 by the operator moves lever 25 in a counterclockwise direction about its pivot thus moving the toggle mechanisms toward straightened position.

The bed construction is more clearly seen in Fig. 3 and comprises a central portion 29 adapted to coact with the central portion 16 of the head and side portions 30 each adapted to coact with one of the side portions 17 of the head. Common cover means encloses the side and central portions of the bed, that shown comprising a spring padding 31 and a cover cloth 32. The side portions of the bed are mounted for lateral movement relative to the central portion thereof, the particular structure shown comprising bell crank members 33 pivotally supported at 34 on the central portion of the bed and having a downwardly extending arm connected with the side portions 30 of the bed while the inwardly ex-

tending arm of the bell crank has a slotted connection at 35 with a pin 36 which in turn is carried by a rod 37 connected at its lower end with a bracket 38 on the treadle 28. A spring 39 surrounds the lower end of rod 37 in a manner to be compressed between a ball 40 on the end of the rod and the bracket 38 when the treadle is moved downwardly so that the bracket 38 exerts a yielding action downwardly on the rod 37. Between the frame 10 and a collar 41 on rod 37 a spring 42 is mounted normally tending to bias the rod 37 in an upward direction. The upper position of this rod together with the corresponding position of the bell crank levers 33 is indicated in dot-dash lines in Fig. 3. In this position the side pressing portions or wings 30 of the bed are retracted from the corresponding coacting portions of the head. The actuated position of rod 37 after it has been moved downwardly is indicated in full lines in Figs. 2 and 3 and at this time the coacting side pressing portions of the head and bed are in engagement.

The operation of the mechanism is as follows: With the parts in the full line position of Fig. 1, the operator completes the lay of the work on the bed 12 and presses downwardly on treadle 28. The toggle mechanism moves toward straightened position until the parts reach the dot-dash position of Fig. 1 at which time the central portions of the pressing members are in engagement. Thereafter continued pressure on treadle 28 moves the toggle mechanism to the position of Fig. 2 which takes up the yieldable connection between shoulder 23 of toggle link 18 and the head lever while maintaining yielding pressure against the head lever by means of spring 22. This final movement of the treadle 28 exerts yielding pressure between bracket 38 and the ball 40 on the lower end of rod 37 and yieldingly exerts a downward pressure on rod 37 which moves the bell crank levers 33 to the full line position of Fig. 3, whereupon the press is completely closed. The treadle 28 is held in its operated position by the engagement of a pin 43 on the treadle engaging in a notch 44 of a latching lever 45. At the close of the pressing operation, depression of latching lever 45 releases the treadle 28 and a spring 46 connected between the frame and the rear end of the head lever returns the parts to open position.

What I claim is:

1. In a press of the class described, the combination of a pair of relatively movable coacting pressing members each having a central portion and depending side portions, the side portions of one of said members being movable relative to said central portion thereof, means for moving the central portions of said members into pressing engagement, means for moving said movable depending side portions of one member into pressing engagement with the side portions of the other member, and one actuator for both means.
2. In a press of the class described, the combination of a pair of relatively movable elongated coacting pressing members each having a central portion and depending side portions, the side portions of one of said members being movable relative to said central portion thereof, means for moving the central portions of said members into pressing engagement, means for moving said movable depending side portions of one member into pressing engagement with the side portions of the other member, and each of said means acting through a yielding connection.
3. In a press of the class described, the combination of a pair of coacting relatively movable pressing members each having a central portion and depending side portions, the side portions of one of said members being movable angularly relative to said central portion thereof, means including an actuator for moving the central portions of said members into pressing engagement, said means having a yielding connection providing additional movement of said actuator beyond the point necessary to engage said central portions, and means actuatable upon said additional movement and operable to move said movable depending side portions of one member into pressing engagement with the side portions of the other member.

4. In a press of the class described, the combination of a pair of coacting relatively movable pressing members each having a central portion and depending side portions, the side portions of one of said members being movable angularly relative to said central portion thereof, means including an actuator for moving the central portions of said members into pressing engagement, said means having a yielding connection providing additional movement of said actuator beyond the point necessary to engage said central portions, and means actuatable upon said additional movement and operable to move said movable depending side portions of one member into pressing engagement with the side portions of the other member.

5. In a press of the class described, the combination of a pair of coacting relatively movable pressing members each having a central portion and depending side portions, the side portions of one of said members being movable angularly relative to said central portion thereof, means including an actuator for moving the central portions of said members into pressing engagement, said means having a yielding connection providing additional movement of said actuator beyond the point necessary to engage said central portions, and means actuatable upon said additional movement and operable to move said movable depending side portions of one member into pressing engagement with the side portions of the other member.

6. In a press of the class described, the combination of a pair of coacting relatively movable pressing members each having a central portion and depending side portions, the side portions of one of said members being movable angularly relative to said central portion thereof, means including an actuator for moving the central portions of said members into pressing engagement, said means having a yielding connection providing additional movement of said actuator beyond the point necessary to engage said central portions, and means actuatable upon said additional movement and operable to move said movable depending side portions of one member into pressing engagement with the side portions of the other member.

7. In a press of the class described, the combination of a pair of coacting relatively movable pressing members each having a central portion and depending side portions, the side portions of one of said members being movable angularly relative to said central portion thereof, means including an actuator for moving the central portions of said members into pressing engagement, said means having a yielding connection providing additional movement of said actuator beyond the point necessary to engage said central portions, and means actuatable upon said additional movement and operable to move said movable depending side portions of one member into pressing engagement with the side portions of the other member.

8. In a press of the class described, the combination of a pair of coacting relatively movable pressing members each having a central portion and depending side portions, the side portions of one of said members being movable angularly relative to said central portion thereof, means including an actuator for moving the central portions of said members into pressing engagement, said means having a yielding connection providing additional movement of said actuator beyond the point necessary to engage said central portions, and means actuatable upon said additional movement and operable to move said movable depending side portions of one member into pressing engagement with the side portions of the other member.

nnection and to actuate said side portion moving means.

8. In a press of the class described, the combination of a frame, a head lever pivotally mounted thereon, a head member carried by the lever, a bed member on the frame, each of said members having a central portion and depending side portions, the side portions of said bed being movable laterally relative to the central portion thereof, toggle means having a yielding connection with the head lever and movable toward straightened position for causing pressure en-

gagement between the central portions of said members, a treadle for so moving said toggle means, means for moving the side portions of said bed member laterally into pressing engagement with the side portions of said head member, and a connection between said treadle and said side portion moving means and adapted to actuate the latter when the treadle is moved to take up on said yielding connection between the toggle means and head lever. 5 10

GEORGE W. JOHNSON.
